Primary Examiner — Susan E Krakower(74) *Attorney, Agent, or Firm* — Thorpe North & Western LLP**CLAIM**

The ornamental design for a backboard with extendable handles for transporting a patient, as shown and described.

DESCRIPTION

FIG. 1 is an elevated, perspective view of the backboard with extendable handles for transporting a patient in accordance with my invention;

FIG. 2 is a top view thereof;

FIG. 3 is a bottom view thereof;

FIG. 4 is an enlarged top end view thereof;

FIG. 5 is an enlarged bottom end view thereof;

FIG. 6 is a left side view thereof;

FIG. 7 is a right side view thereof; and,

FIG. 8 is a bottom perspective view thereof.

The broken lines shown in FIGS. 1-8 illustrate environmental structure and form no part of the claimed design.

1 Claim, 5 Drawing Sheets(56)
